UNITED STATES PATENT OFFICE.

ELIAS B. REQUA, OF JERSEY CITY, NEW JERSEY.

LANTERN.

SPECIFICATION forming part of Letters Patent No. 224,225, dated February 3, 1880.

Application filed December 12, 1879.

To all whom it may concern:

Be it known that I, ELIAS B. REQUA, of Jersey City, in the county of Hudson and State of New Jersey, have invented certain new and useful Improvements in Lanterns, of which the following is a specification.

This invention relates to the class of lanterns adapted for burning light hydrocarbons.

Its object is to supply the burner and globe with an abundance of air for the support of the flame and for carrying off the products of combustion, to increase the illuminating power of the lantern by causing the flame to extend higher into the globe than heretofore, and to prevent flickering of the flame.

It consists mainly, first, in a lantern having the lower end of its globe closed by an inwardly-extending deflector provided with a flame-slot, said deflector resting upon an annular foraminous corrugated band or wall which surrounds the burner, whereby a reservoir of air is formed around the burner, and the inward flow of air thereto, while ample in quantity and evenly distributed, has its current-force checked; second, in a lantern having the lower end of its globe closed by an inwardly-extending deflector provided with a flame-slot, said deflector resting upon an annular foraminous corrugated band or wall enclosing the top of the oil-fount and surrounding the burner, the said fount being provided with air-passages leading from its bottom to within said foraminous band or wall, and said fount being further provided with foraminous screens or walls arranged between the lower ends of its air-passages and the outer air.

By this arrangement a supply of air is guaranteed from the bottom of the lantern, and also laterally above the oil-fount, and the two flows are caused to impinge upon each other and neutralize each other's force. The screens and foraminous walls subdivide the flow of air, check its force, and cause an even distribution of air around the flame.

In the accompanying drawings, Figure 1 is a view, in elevation, of a lantern embracing my improvement. Fig. 2 is a vertical diametric section of same. Fig. 3 is a top perspective view of the base with the globe and its combined holder and deflector removed. Fig. 4 is a perspective view of the false bottom de-

tached, and Fig. 5 is a plan view of the combined globe-holder and deflector detached.

The letter A indicates the oil-fount, supplied with a burner, B, of any suitable construction, 55 having an air-chamber surrounding its wick-tube. Upon the top of the oil-fount is arranged a foraminous corrugated band, C, encircling the burner, and having a diameter about equal to the base of a combined globe-holder and deflector, D, which rests upon it. This globe-holder and deflector is approximately cone-shaped, flaring somewhat abruptly at its base, and having a flange, b, extending upward from its edge, and provided with a 60 lip, c, which is the portion of the deflector which bears immediately upon the band C. Within the flange b fits the base of the globe E, and the flaring portion of the cone is provided with rows of perforations.

Vertically through the oil-fount are arranged air-passages f, and the said fount is provided with a foraminous base-rim, g, permitting free access of air to the lower ends of said passages. Below the bottom of the oil-fount is hinged a 70 false bottom, h, having a central aperture, around the edge of which is arranged a foraminous wall, i, from which radiate four perforated walls, k, so that when the false bottom is closed the space between the bottom is divided into 75 four chambers, into each of which opens one of the air-passages f, passing through the fount.

The letter L designates the lantern-cap, consisting of an upwardly-tapering band, m, fitting upon the top of the globe and surrounded by another band, n, the lower edge of which rests upon the wall of the inner band and has recesses o in it, forming air-passages. The inner band, m, has around its base a row of perforations, r, which admit air to its interior to reinforce the upward draft and cause a rapid exit of the products of combustion from the globe. The outer band extends somewhat above the other, and has upward-projecting arms p, which support a dished disk, q, which is the 95 cover of the cap. The cap is hinged in the ordinary manner to one of the globe-guards, and is secured to the other by a spring-catch.

The operation of the lantern is as follows: When the wick in the burner is lighted air 100 flows through the perforated wall of the base of the fount and through the aperture of the

the false bottom and the foraminous walls to the air-passages *f*, through which it flows to the space inclosed by the serpentine or corrugated band *C*, surrounding the base of the burner, 5 and thence, through the foraminous wall of the base-chamber of the burner, it flows to the base of the flame. A large amount of air is thus supplied to the flame and its initial current-force considerably checked; but it is still liable to assume the form of separate upward currents, which it is desirable to disperse and mingle to form a general store of air, giving an evenly-distributed supply all around the base of the flame. This object is accomplished 15 by the laterally-inward flow of the air through the perforations of the serpentine or corrugated band *C*, which is given its peculiar form in order that it may intercept currents of air flowing in any direction and have a large surface and a great number of fine perforations 20 to permit the passage of a great amount of air evenly distributed, the flow of which impinges against the air flowing up through the passages *f*, breaks its force, and causes it to spread 25 under the deflector *D*, so that the flame draws its supply from a still reservoir of ample capacity. A portion of the air from the reservoir flows through the perforations in the flaring portion of the deflector *D*, and creates an upward current through the globe, which carries 30 upward the products of combustion. This current is re-enforced by the air flowing into the cap *L* through the perforations *r*, so that the products of combustion are caused to pass 35 rapidly from the globe without leaving any deposit thereon, and the air flowing through the apertures upward between the inner and outer bands of the cap, and then escaping under the edges of the cover *q*, forms at the top of the 40 cap outward lateral currents, which prevent any portion of the products of combustion from being reflected back into the globe.

It will be observed that, as the deflector *D* directs a very large supply of air upon the flame and through its flame-slot, the flame will 45 be caused to extend high up into the globe, and thus the radiation of light will be but little intercepted by the base portions of the lantern.

Having fully described my invention, what 50 I claim is—

1. A lantern having the lower end of its globe closed by an inwardly-extending deflector provided with a flame-slot, said deflector resting upon an annular foraminous corrugated band which surrounds the burner, substantially as and for the purpose set forth. 55

2. A lantern having the lower end of its globe closed by an inwardly-extending deflector provided with a flame-slot, said deflector resting upon an annular foraminous corrugated band or wall encircling the top of the oil-fount and surrounding the burner, the said fount being provided with air-passages leading from its bottom to within said foraminous band or wall, and said fount being further provided with foraminous screens or walls arranged between the lower ends of its air-passages and the outer air, substantially as and for the purpose set forth. 60 65

3. The combination of the oil-fount having the air-passages therethrough, the false bottom provided with the perforated walls and central aperture, the foraminous corrugated wall surrounding the top of the oil-fount and burner, and the deflector resting upon said wall, substantially as described. 70 75

In testimony that I claim the foregoing I have hereunto set my hand and seal in the presence of the subscribing witnesses.

ELIAS B. REQUA. [L. S.]
